UNITED STATES PATENT OFFICE.

WILLIAM E. BECK, OF BIRMINGHAM, ENGLAND.

STAND FOR WATCHES.

1,340,859.

Specification of Letters Patent.

Patented May 18, 1920.

Application filed March 10, 1920. Serial No. 364,829.

To all whom it may concern:

Be it known that I, WILLIAM ERNEST BECK, a subject of the King of Great Britain, residing at 73 Linden road, Bournville, 5 Birmingham, in the county of Warwick, England, have invented a certain new and useful Improved Stand for Watches; and I do hereby declare the following to be a full, clear, and exact description of the same.

10 My invention comprises a new or improved stand or clip for watches and has for its object to provide an extremely simple and cheap stand which will effectively support a watch as say in a bedroom or on a 15 table or in a shop, the invention being particularly useful for supporting luminous watches by the bedside, or for exhibiting watches on shelves or for projecting watches from the edge of a shelf as in shop windows. 20 According to this invention the support has a pair of spring arms adapted to embrace the pendant of the watch, and a strut member disposed between the spring arms and adapted to bear upon the pendant of 25 the watch in such manner that only a limited movement is permitted between the watch and stand.

The stand may also incorporate a spring clip for attachment to the edge of a shelf.

30 Referring to the drawings:—

Figure 1 is a view in elevation of one form of the device.

Fig. 2 is a perspective view showing the device in use.

35 Fig. 3 is a longitudinal section.

Fig. 4 is a plan view of another form of the device.

Fig. 5 is a side view of the form shown in Fig. 4.

40 In the construction shown in Figs. 1, 2 and 3, the device is shown as arranged for supporting a watch upon a table; the stand 1 is pressed from sheet metal and may be conveniently of a more or less triangular 45 form, *i. e.*, two feet 2, 2 at the base and an upstanding portion which is provided with long slots 3, 3 dividing the upper part into two spring arms 4, 4 adapted to embrace the pendant with a strut portion 5 between them. The extremities of the two parts 4 are rounded and the slots 3 are narrow at the ends but widen so that the arms 4 may be sprung around the pendant, which is firmly held when it is located in the wide 50 portion at the end of the slots.

55 The strut 5 may conveniently be formed

integral with the stand and the spring arms 4 as shown. Alternatively, the strut 5 may be stamped from another part of the stand and bent to bring it into the required position. As shown the strut 5 is slightly shorter than the spring arms 4 and it is shaped to fit against the back of the pendant and is preferably bent so as to lie in a plane 60 slightly above that of the spring arms 4. 65

The upper ends of the spring limbs 4 are bent over toward the front of the pendant while the strut 5 forms an abutment at the back thereof at a higher level in such manner as to limit the angular movement between the stand and watch so as to prevent them falling over.

The bottom of the watch and the two legs of the stand thus together constitute a three-point suspension.

75 The invention is also applicable for displaying watches on shelves or from the edges of shelves in shops, in which latter case the stand may be formed integral with, or secured to, a spring clip portion adapted to 80 engage with the edge of a shelf whereby watches may be projected forwardly from the edge of a shelf in a safe and secure manner and at such an angle as to most effectively display the face of the watch. This 85 clip may also carry a price card or the like.

A device of this kind is shown in Figs. 4 and 5 wherein a single piece of sheet material, preferably spring steel, is cut and bent as shown to provide a clip 6 adapted 90 to grip firmly on to the edge of a shelf or the like. The metal of which the clip is formed is cut along lines 7, 8, 9 and 10 forming between those lines a pair of spring arms 11, 11 and a strut 12. These spring 95 arms 11 and strut 12 operate between them to support a watch. The device is shown in use in Fig. 5 with the pendant of the watch gripped between the spring arms 11 and supported by the strut 12 which, in this 100 construction, is at a lower level than the spring arms 11.

The metal of which the clip is made may also be cut as shown at 13 and the severed tongue of metal 14 may be bent as shown. 105 The tongue 14 may be further cut as shown at 15 to provide a spring clip for holding a price or announcement card as 16.

110 It will be understood that in this construction any one or more of the tongues of metal forming the spring arms or the strut may be made separately and secured to the

clip 6 by riveting or by other means. Or the stand might be made from wire bent to the configuration of the sheet metal stand illustrated upon the drawings and including the arms and strut.

What I claim then is:—

A watch support provided with a pair of spaced arms shaped in their opposing sides to fit opposite sides of a watch pendant, and 10 with a strut, between said arms and of less

length than said arms and arranged to bear, at its outer end, against one side of the pendant.

In testimony whereof I affix my signature in presence of two witnesses.

WILLIAM E. BECK.
